[57] CLAIM

The ornamental design for a handle for a fishing rod, as shown and described.

DESCRIPTION

FIG. 1 is an elevational view of one side of a handle for a fishing rod showing our new design;

FIG. 2 is a top plan view thereof;

FIG. 3 is a bottom plan view thereof;

FIG. 4 is a front elevational view thereof;

FIG. 5 is a rear elevational view thereof.

The broken line showing of the rod, foregrip, reel nut and end cap is for environmental purposes only and forms no part of the claimed design.

FIG. 1

FIG. 2

FIG. 3

FIG. 4

FIG. 5
